UNITED STATES PATENT OFFICE.

CONRAD T. HANSEN, OF DETROIT, MICHIGAN, ASSIGNOR TO THE AMERICAN MOTOR BODY CORPORATION, OF PHILADELPHIA, PENNSYLVANIA, A CORPORATION OF DELAWARE.

DESIGN FOR A SEAT END.

Application filed March 19, 1924. Serial No. 9,002. Term of patent 14 years.

To all whom it may concern:

Be it known that I, CONRAD T. HANSEN, a citizen of the United States, residing at Detroit, in the county of Wayne and State of Michigan, have invented a new, original, and ornamental Design for Seat Ends, of which the following is a specification, reference being had to the accompanying drawing, forming part thereof.

The figure is a perspective view of a seat end, showing my new design.

I claim:

The ornamental design for a seat end, as shown.

This specification signed this 10th day of March, 1924.

CONRAD T. HANSEN.
